UNITED STATES PATENT OFFICE.

ISAAC LUTZ, OF FRANKFORT, MICHIGAN.

DEVICE FOR RELIEVING CHOKE IN ELEVATOR-BOOTS.

SPECIFICATION forming part of Letters Patent No. 749,071, dated January 5, 1904.

Application filed August 21, 1903. Serial No. 170,370. (No model.)

To all whom it may concern:

Be it known that I, ISAAC LUTZ, a citizen of the United States of America, residing at Frankfort, in the county of Benzie and State of Michigan, have invented certain new and useful Improvements in Devices to Relieve Choke in Elevator-Boots, of which the following is a specification.

This invention relates to conveyers, and particularly to that subclass thereunder known as "endless-conveyer boots."

An object of the invention is to overcome a tendency of the grain to choke within the boot and to relieve the pressure on the conveyor in case of choking.

Furthermore, an object of the invention is to provide novel means which will relieve the pressure within the boot and at the same time guard against wasting of grain or other material which is being acted upon.

A still further object of the invention is to produce novel means for retaining the relieving device in place and permitting its release automatically when a predetermined pressure has been applied within the boot.

Furthermore, an object of the invention is to produce a pressure-releasing device of the character noted which will possess advantages in points of simplicity, efficiency, and durability, proving at the same time comparatively inexpensive to produce and maintain.

With the foregoing and other objects in view the invention consists in the details of construction and in the arrangement and combination of parts to be hereinafter more fully set forth and claimed.

In describing the invention in detail reference will be had to the accompanying drawings, forming part of the specification, wherefore in like characters denote corresponding parts in the several views, and in which—

Figure 1 is a sectional view of an elevator-boot with the invention applied thereto. Fig. 2 is a sectional view taken on the line 2 2 of Fig. 1. Fig. 3 is a sectional view taken on the line 3 3 of Fig. 1. Fig. 4 is a perspective view of one of the guards.

In the drawings, 1 indicates a conveyer of ordinary construction which has door-openings 2, usually controlled by sliding shutters or doors.

This invention contemplates the substitution of an automatically-controlled pressure-reliever mounted to guard the door-opening and comprising in its construction two side walls, which fit on the outer surface of the sides of the boot, and a front 3, the said side walls being connected by the front 3, which when the device is in position to close the door-opening fits against the flanges 4 on each side of the said door-opening. Bolts 5 are anchored in the flanges 4 and have threaded ends projecting through slots 6, formed in the sides of the guard. Thumb-nuts are applied to the bolts for binding the sides of the device 55 in contact with the boot in order to prevent displacement under ordinary pressure. The tension of the thumb-nuts may be so regulated as to cause the guard to yield when the pressure within the boot has reached a pre- 60 determined point.

Each guard is provided with a hinge 7, which is secured to the lower end of the front plate 3, one leaf of the spring being secured to the edge of the casing which forms the boot. The hinge is of sufficient width to fit within the opening in order to prevent escape of the grain between the end of the front plate and the casing. The upper end of the front plate has a flange 8, which fits between the flange 85 4, which with the remainder of the closing device completely guards the door-opening.

It will be observed that this guard is duplicated on each end of the boot and that both doors may be employed to relieve the pressure. If desired, the thumb-nuts of one guard may be set with greater tension than that of the other door, so that if the movement of one guard fails to relieve the pressure the other guard will then be operated. 90 Of course it may be desirable to have the tension of the nuts so great as to preclude the movement of the guards except when they are released by an operator after the choking has occurred.

By the use of the guards of the character noted it will be observed that when they are opened to relieve the pressure said guards form a pocket-like receptacle into which the grain from the pocket may be crowded without the usual loss of grain incident to the relief of the pressure within the boot.

The construction, operation, and advantages will, it is thought, be understood from the foregoing, it being noted that various changes may be made in the details of construction without departing from the scope thereof.

Having fully described my invention, what I claim as new, and desire to secure by Letters Patent, is—

- 10 1. In an elevator-boot a body having a door-opening, a guard comprising side and end pieces, having slots transversely disposed, means for hinging the guard in the door-opening, bolts in the slots of the sides and means for clamping the sides against the boot.
- 15 2. In an elevator-boot a body having a door-opening, side flanges for the door-opening, a guard pivoted in the door-opening and having a top flange fitting between the side flanges of the door-opening when the guard is closed, means for hinging the guard in the door-open-
- 20

ing and means for clamping the guard to the boot.

3. In an elevator-boot a body having a door-opening, a flange at each side of the door-opening, a guard comprising sides and an end piece, the said sides having slots therein, a flange on the upper end of the end piece fitting between the flanges of the door-opening, and hinge secured to the inner surface of the end piece at its lower end and secured to the lower edge of the boot-frame forming a door-opening, bolts projecting from the flanges of the boot into the slots of the guard and nuts for clamping the sides to the boot.

In testimony whereof I affix my signature, in the presence of two witnesses, this 4th day of August, 1903.

ISAAC LUTZ.
